UNITED STATES PATENT OFFICE.

GEORGE H. DAWSON, OF BOSTON, MASSACHUSETTS, ASSIGNOR, BY MESNE ASSIGNMENTS, TO RAND KARDEX BUREAU, INC., OF TONAWANDA, NEW YORK, A CORPORATION OF DELAWARE.

CARD HOLDER.

Application filed April 10, 1925. Serial No. 22,116.

This invention relates to a card holder adapted for use in an overlapping visible index and concerns itself primarily with a structure having a releasable fold; said 5 fold forming a sort of pocket for the ready insertion or removal of cards or index matter.

The invention comprises the novel structure and combinations hereinafter described 10 and more particularly pointed out and defined in the appended claims.

In the accompanying drawings which illustrate a preferred embodiment of this invention and in which similar reference numerals refer to similar features in the different views:

Figure 1 is an elevational view of a card holder involving this invention.

Figure 2 is an enlarged sectional view 20 upon the line 2—2 of Figure 1.

Figure 3 is an elevational view of a slightly modified form of card holder.

Figure 4 is an elevational view of the modified card holder in partially unfolded 25 position.

Referring to the drawings which illustrate the chosen embodiment of this invention, it will be observed that there has been shown a rectangular spacing bar 1, the ends 30 of which are adapted to be retained in the guide channels of a supporting frame or tray as is well-known in the art. A flexible hinge member 2 which may consist of paper or any suitable material having a slotted 35 bend line 2^a is secured to the bar 1 and depends therefrom. The lateral margins of this depending portion of the hinge are provided with studs 3 preferably in the form of eyelets. Disks 4 of suitable material are 40 confined upon the outwardly projecting ends of the studs.

The card holder proper consists of fairly 45 rigid sheet or fibrous material which can be readily folded and which will retain its shape. The holder consists of a back or rear portion 5, a lower fold 6 and an upper fold 7 which overlaps a part of the lower fold. The lateral edges of the rear portion may be provided with inturned folds 50 8 as shown in the modified form. These lateral or inturned folds are adapted to be confined beneath the upper and lower folds as shown in Figure 3.

The lateral margins of the upper portion

of the card holder are notches as indicated 55 at 9 for the reception of the studs 3 which extend through both thicknesses of said holder. The holder may be mounted upon the studs by flexing the same upon a vertical line and engaging the notches with the 60 studs.

It will be appreciated that the disks 4 overlap the slots 9 in the folded portion 7 and maintain the fold 7, against the overlapped portion of the lower fold 6, thus 65 otherwise retaining the lower folded portion in folded position. It is however, possible to sufficiently flex the upper fold 7 on a line adjacent the lower parts of the disks 4 to allow the lower fold 6 to be unfolded for 70 the reception or removal of cards or index matter.

I am aware that numerous details of construction may be varied through a wide 75 range without departing from the principles of this invention, and I therefore do not purpose limiting the patent granted otherwise than necessitated by the prior art.

I claim as my invention:

1. A card holder comprising a supporting means having spaced studs, retaining disks upon said studs, a sheet having an upper folded portion provided with lateral notches for receiving said studs, and a lower fold partially extending into the upper 80 folded portion and confined thereby.

2. A card holder comprising a sheet having a lower fold and an upper fold partially overlapping the lower fold, and supporting means extending through the upper 90 folded portion of the holder for maintaining said folds in their folded positions.

3. A card holder comprising a sheet having a lower fold, an upper fold partially overlapping said lower fold, and lateral 95 folds confined beneath said upper and lower folds, in combination with supporting means extending through the upper fold for maintaining said folds in their folded positions.

4. A card holder comprising a sheet having upper and lower overlapping folded portions, and a support having means extending through one of said folded portions for maintaining the folded relation of said portions.

5. A card holder comprising a sheet having upper and lower overlapping folded portions, a support therefor having means for

releasably engaging one of said folded portions, said means tending to maintain the folded relation of said portions.

6. A card holder comprising a sheet having upper and lower overlapping folded portions and a support therefor having means for engaging one of said folded portions for maintaining the folded relation thereof.

7. A card holder comprising a sheet having upper and lower folded portions and a support therefor having means engaging over one folded portion for maintaining the folded relation thereof.

8. A card holder comprising a sheet having upper and lower overlapping folded portions, and a support therefor having spaced headed studs, one of said folded portions being laterally notched for receiving said studs.

20 9. In a card holder, the combination with

a spacing bar, the ends of which are adapted to be retained in guide channels, of a sheet supported by said spacing bar having an upper folded portion, and a lower folded portion on said sheet partially extending ²⁵ into the upper folded portion and confined thereby.

10. In a card holder, the combination with a spacing bar, the ends of which are adapted to be retained in guide channels, of a sheet ³⁰ supported by said bar and having a bend line adjacent said bar, an upper folded portion associated with said sheet, and a lower folded portion on said sheet partially overlapping the upper folded portion so as to ³⁵ be releasably confined thereby.

In testimony whereof I have hereunto subscribed my name.

GEORGE H. DAWSON.
